DEVICE FOR CONTINUOUSLY MIXING TEXTILE FIBRES

Hans Schweizer, Luino, Italy, assignor to Aktiengesellschaft Joh. Jacob Rieter & Cie, Winterthur, Switzerland, a corporation of Switzerland

Application August 4, 1951, Serial No. 240,334

Claims priority, application Switzerland August 7, 1950

4 Claims. (Cl. 19—146)

The present invention relates to a device for continuously mixing textile fibres.

It is customary in spinning mills to assemble all of the raw material necessary for filling an order, for example, a number of cotton bales, material to be admixed such as rayon staples, and left-overs from previous orders such as slivers and flyer slubbings, before the spinning process is started. It is essential that the length of staple of all components is substantially the same; all fibres must be thoroughly mixed before and also during the spinning process to produce a yarn of uniform color, strength, and elongation. It is an object of the present invention to provide a means for producing the aforementioned conditions at small cost, by means of simple mechanisms, and with little and unskilled labor. The device according to the invention is suitable for preparing small batches of well mixed material in uninterrupted operation.

With the apparatus according to the invention, fibres of the same type are spread out in layers, whereupon layers of different fibres are superimposed in horizontal position to form a pile containing fibres of all components of the mixture; at least two so produced piles are placed on top of one another and separated by swingable plates, whereupon material is removed continuously from one pile after the other at a slant to the layers.

Further and other objects of the present invention will be hereinafter set forth in the accompanying specification and claims, and shown in the drawings which, by way of illustration, show what I now consider to be a preferred embodiment of my invention.

In the drawings:

Fig. 1 is a diagrammatic vertical sectional front view of a hopper feeder having an extended hopper according to the invention;

Fig. 2 is a diagrammatic top view of a bale opener and feed lattice with bales laid out therealong;

Fig. 3 is a part sectional side view of the feeder shown in Fig. 1;

Fig. 4 is a diagrammatic illustration of a counting device to be used in combination with the feeder shown in Figs. 1 and 3;

Fig. 5 is a sectional large scale view of a detail of Fig. 3.

Like parts are designated by like numerals in all figures of the drawings.

Referring more particularly to Fig. 2 of the drawings, numeral 2 designates a feed lattice alongside of which the material to be fed into a bale opener 1 is placed, fourteen cotton bales B being shown. The material is conducted through conduit 3 from the bale opener 1 into a discharge device 4 which throws the material on a conveyor lattice 5. The latter is built into a frame 6, supported by rollers 7 having axles to which lattice drums 8 are connected. Rollers 7 run on rails 9 arranged along the top of the long side walls of a case or hopper 10 whose cross-section is rectangular. Parts 4 to 10 are illustrated in Fig. 1.

Frame 6 is rolled back and forth along the top of hop-

2

per 10 by means of a chain 11 or similar flexible means looped around two rollers, one of which is driven by a motor 19 through gear wheels 16, 17, and 18. Chain 11 is provided with a laterally protruding pin 13 which 5 slides in a slot 14 in a part 15 vertically projecting from frame 6.

A horizontal lattice conveyor 20 is provided at the bottom of hopper 10. A substantially vertical, spiked lattice 21 is so positioned at the right end of lattice 20, 10 in Fig. 1, that it takes over the material brought along by the latter. Lattice 21 is slightly inclined toward the right in Fig. 1. Casing 22 closes the descending part of lattice 21 against the outside. A fluted roller 23 depresses the material brought up by lattice 21 and clearer 24 removes the material from the spikes of lattice 21 and into the discharge duct 25. Horizontal, laterally swingable plates 26 (Fig. 3) divide the hopper 10 into two chambers. The plates 26 are portions of angularly bent plates whose vertical portions 27 form the side walls of 20 the hopper 10. Plates 26, 27 depend from horizontal shafts 28 placed along the top of the sides of the hopper. The free ends of arms 29 extending from shafts 28 are connected by links 30 with rod 31 of an operating piston 32 (Fig. 5). The latter is in a cylinder 33 having ports 34 and 35 for admission and relief of a working fluid. Alongside cylinder 33 is a control cylinder 36 which 25 communicates with the former through the ports 34 and 35 and contains a valve having two pistons 39 on a rod 41. Top and bottom of cylinder 36 have outlets 38 and 37, respectively. A supply conduit 40 is connected with the middle of cylinder 36 for conducting a pressure fluid into the space 41' between pistons 39. The lower end of rod 41 is pivoted to the left arm of lever 42 to whose 30 right arm the upper end of rod 43 is pivoted. The lower end of rod 43 is pivoted to an arm 44 extending from shaft 44' from which depends a regulating flap 45. Arm 44 carries a weight 44" displaceable thereon for counter-balancing the weight of flap 45 and providing the force 35 needed for moving the control pistons 39.

The counting device shown in Fig. 4 comprises a ratchet wheel 46 and a pawl 47 forming part of a lever pivoted to arm 48 of an angular lever whose other arm 49 carries a weight 49' which is displaceable. After each 40 full travel of chain 11, pin 13 lifts arm 49 causing lever 48, 49 to swing counter-clockwise and move pawl 47 into the next following tooth gap of the ratchet wheel 46, a stationary abutment 48' preventing excessive movement of the lever 48. After pin 13 has left arm 49, weight 49' pulls lever 48, 49 clockwise. The dimensions of the pawl 47 and of the lever 48, 49 are such that the pawl 47 advances wheel 46 clockwise by one tooth. Pawl 50 locks wheel 46 against counter-clockwise movement. A pin 51 is mounted in a slot in wheel 46 so that its position can be changed. Pin 51 moves with the wheel until it abuts 45 against a plate 52' at one end of a rod 52 whose other end is pivoted to a switch 53. This switch controls the current for operating a motor 1' driving the bale opener 1 and is opened against spring 60.

Operation of the device

The operator moves material from bales B onto the lattice 2, the amount corresponding to the amount necessary for producing a layer c in hopper 10. The bale opener 1 loosens the fibre mass to clusters which are 50 thrown by the discharge device 4 onto the lattice 5. The latter moves back and forth with the frame 6 over the hopper 10 and moves supplementally in the same direction as frame 6 at a speed depending on the size of the wheels on the frame and the diameter of the rollers 55 supporting the lattice 5. The absolute speed of the surface of the upper run of lattice 5 is twice as great as that of the frame, and the material on the lattice is thrown 60

over the ends of the lattice, i. e. over the rollers 8 onto the plates 26. Upon movement of frame 6 to the left, half layer I-II is produced and upon return of the frame half layer I-III is produced. This is repeated until a predetermined number of layers c are placed in the upper part of hopper 10. The number of layers c is defined by suitable setting of pin 51 on ratchet wheel 46. The number of teeth by which the latter is advanced until pin 51 abuts plate 52' corresponds to the desired number of layers c. Abutment of pin 51 against plate 52' causes rod 52 to open switch 53 and to stop the motor 1' of the bale opener 1, so that supply of material from the bale opener is interrupted. Thereupon, frame 6 idles back and forth and pawl 47 continues to turn wheel 46, and pin 51, abutting plate 52' moves rod 52 further to the left and increases compression of spring 60. When the spring 60 is so much compressed that further compression by the action of the weight 49' through the lever 48, the pawl member 47, the ratchet wheel 46, and the pin 51 is not possible, the pin 13 may lift the weight 49' once more, moving the pawl 47 to the left for engaging a new tooth of the wheel 46. The weight 49', however, will not be able to rotate the wheel 46 and will stay in the elevated position until the flap 45 rises, causing counterclockwise rocking of the pawl 50 and disengagement of the pawl 47 from the ratchet wheel 46 so that the latter can be rotated counterclockwise by the weight 56 and the rope 57. Meanwhile lattice 20 moves the previously deposited stack which is in the lower part of hopper 10 toward the spiked lattice 21 which picks material equally from all layers and moves it upward. As soon as the stack in the lower part of hopper 10 releases flap 45, the latter moves clockwise into the position shown in dotted lines in Fig. 3. This causes movement of control piston by the mechanism 44, 43, 42 and rod 41 into the position shown in Fig. 5. The pressure medium in the lower part of cylinder 33 can now escape through port 35 and conduit 37. If a medium other than air is used, this is returned to pump P. The space 41' between pistons 39 affords flow of fluid from conduit 40 and through port 34 into the space above piston 32, forcing the latter down. Rod 31 pulls links 30 and levers 29 down, causing turning of shafts 28 and outward swinging of plates 26, so that the stack in the upper part of the hopper drops onto lattice 20. Regulating flap 45 is thereby pressed counter-clockwise into the position shown in solid lines in Fig. 3. Rod 41 is thereby pulled down and piston member 39 is moved into a position where port 34 is connected with relief conduit 38, and pressure fluid flows from conduit 40 through port 35 below piston 32 forcing the latter and rod 31 up. This causes inward movement of plates 26 to form a bottom for the upper part of hopper 10. When plates 26 were moved outward, lever 54 fast on the left rod 28 moved rod 55 linked to the free end of the lever upward, thereby releasing the locking pawl 50 (Figs. 3 and 4) from the ratchet wheel 46 and lifting pawl 47 out of engagement with wheel 46. The latter can now be turned counter-clockwise by a weight 56 which unwinds a rope 57 or the like from the shaft of wheel 46. Counter-clockwise revolving of the wheel continues until pin 51 abuts against a stationary abutment 58. Rod 52 can now be returned by spring 60 to its original position and closes switch 53 for restarting motor 1', whereupon material is again delivered to discharge device 4. Locking pawl 50 resumes its normal position as soon as plates 26 return to closed position.

While I believe the above described embodiment of my invention to be a preferred embodiment, I wish it to be understood that I do not desire to be limited to the exact details of design, and construction shown and described, for obvious modifications will occur to a person skilled in the art.

I claim:

1. An apparatus for continuously mixing different kinds of textile fibres, comprising, in combination, a case having

a lower and an upper part, a spiked, substantially upright lattice at one side of said case, a horizontal conveyor lattice disposed at the bottom of said lower part for moving textile fibres in said lower part toward said spiked lattice, angular plate members laterally swingably connected with the upper part of said case, each plate member having a first portion forming a side wall of said upper part and a portion rigidly connected with said first portion inside said case and forming a bottom for the upper part thereof when said plate members are not laterally swung, and fibre distributing means disposed above said upper part for distributing fibres thereto.

2. An apparatus for continuously mixing different kinds of textile fibres, comprising, in combination, a case having a lower and an upper part, a spiked substantially upright lattice at one side of said case, a horizontal conveyor lattice disposed at the bottom of said lower part for moving textile fibres in said lower part toward said spiked lattice, plate members individually having an upright portion laterally swingably connected at its top with said case and forming a side wall of said upper part and having a portion extending at an angle from said upright portion inside said case and forming a bottom for the upper part thereof when said plate members are not laterally swung, fibre distributing means disposed above said upper part for distributing fibres thereto, a cylinder containing a piston adapted to be moved in said cylinder by a pressure fluid, and connecting means between said piston and said plate members for swinging same simultaneously upon movement of said piston in said cylinder.

3. An apparatus for continuously mixing different kinds of textile fibres, comprising, in combination, a case having a lower and an upper part, a spiked substantially upright lattice at one side of said case, a horizontal conveyor lattice disposed at the bottom of said lower part for moving textile fibres in said lower part toward said spiked lattice, plate members laterally swingably connected with the upper part of said case, each member having a first portion forming a side wall of said upper part and a portion extending at an angle from said first portion inside said case and forming a bottom for the upper part thereof when said plate members are not laterally swung, fibre distributing means disposed above said upper part for distributing fibres thereto, said distributing means comprising a frame horizontally rollingly supported on top of said upper part, a conveyor lattice built into said frame, means for rolling said frame back and forth and simultaneously moving said built-in lattice in the same direction as said frame for discharging fibres from said lattice over its ends, means disposed above said frame for discharging textile fibres onto said built-in lattice, means supplying fibres to said discharging means, counting means connected with said distributing means for counting the number of reciprocations of said frame, means connected with said counting means and responsive to a predetermined number of reciprocations of said frame and connected with said fibre supplying means for stopping operation of the latter after a predetermined number of movements of said frame, reversing means associated with said counting means, locking means cooperating with said counting means and actuated by said laterally swingable plate members for locking said counting means against the action of said reversing means when said plate members are not laterally swung and adapted to unlock said counting means for reversal by said reversing means when said plate members are laterally swung.

4. An apparatus for continuously mixing different kinds of textile fibres, comprising, in combination, a case having a lower and an upper part, a spiked substantially upright lattice at one side of said case, a horizontal conveyor lattice disposed at the bottom of said lower part for moving textile fibres in said lower part toward said spiked lattice, plate members individually having an upright por-

tion laterally swingably connected at its top with said case and forming a side wall of said upper part and having a portion extending at an angle from said upright portion inside said case and forming a bottom for the upper part thereof when said plate members are not laterally swung, fibre distributing means disposed above said upper part for distributing fibres thereto, a cylinder containing a piston adapted to be moved in said cylinder by a pressure fluid, connecting means between said piston and said plate members for swinging same simultaneously upon movement of said piston in said cylinder, a flap member swingably connected with the lower part of said case, means yieldingly holding said flap member in one extreme position when said lower part is partly empty so as to clear said flap member, said flap member being swung against the action of said last mentioned means by the fibres in said lower part when it is full, and control means for the pressure fluid in said cylinder, said control means

being connected with said flap member and actuated thereby for moving said piston to laterally swing said plate members when said lower part is empty for affording the material in the upper part to drop into the lower part of the case.
